By Frank H. Marks, Atty.

UNITED STATES PATENT OFFICE

107,088

DESIGN FOR WALLPAPER OR SIMILAR ARTICLE

John R. Morgan, Oak Park, Ill., assignor to Sears, Roebuck and Co., Chicago, Ill., a corporation of New York

Application October 8, 1937, Serial No. 72,068

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for Wallpaper or Similar Article, of which the following is a specification, reference being had to the accompanying drawing, forming a part thereof.

The drawing is a plan view of wallpaper or similar article, embodying my new design.

I claim:

The ornamental design for wallpaper or similar article, as shown.

JOHN R. MORGAN.
